Louis O. French

ATTORNEY.

UNITED STATES PATENT OFFICE

MAX P. JANISCH, OF MILWAUKEE, WISCONSIN, ASSIGNOR TO THE GEM HAMMOCK & FLY NET COMPANY, OF MILWAUKEE, WISCONSIN, A CORPORATION OF WISCONSIN

MOP

Application filed June 18, 1928. Serial No. 286,116.

The invention relates to mops.

While mops with heads of sheet metal and provided with pivoted handles are well known in the art, the usual types of pivotal connections have not proven satisfactory in service. It has been usual to provide mop heads of sheet metal with spaced ears struck up from the body of the mop head and projecting above the same to which ears the mop handle is pivotally connected, but with such a construction the ears have to take practically all of the clamping strain and they bend inwardly after a short time and the pivot becomes loose and cannot be tightened up so that the handle can be set to the desired inclination for working. The present invention has been designed to obviate these difficulties by interposing a portion of the mop head itself as a bridge between the ears, above the pivot point for the handle, whereby a strong clamping pressure can be exerted and maintained between the handle socket and the mop head so that the handle can be readily adjusted and maintained in the desired position and the ears of the head are reinforced against strains interposed by the clamping bolt, the preferred construction also having this bridge portion of the head struck upwardly or arched to provide increased strength at this point and also permit ears of sufficient length to be formed integrally therewith and project therefrom without extending materially below the head and thus preventing their marring furniture, floors, etc., with which the mop may come in contact.

A further object of the invention is to provide simple and effective means for connecting the mop body to the mop head.

The invention further consists in the several features hereinafter set forth and more particularly defined by claims at the conclusion hereof.

In the drawings Fig. 1 is a plan view of a mop embodying the invention;

Fig. 2 is a detail sectional view taken on the line 2-2 of Fig. 1;

Fig. 3 is a side elevation view, partly in section, the section being taken along the line 3-3 of Fig. 1.

Referring to the drawings, the numeral 5 designates the mop body, which is of conventional form, consisting of the strands 6 of yarn or other fibrous material which is stitched to a fabric band 7.

The numeral 8 designates the mop head, formed as a sheet-metal stamping, preferably of triangular shape, having an upwardly extending, peripheral flange 9 to which the mop body is secured by rivets 10 that pass through the fabric-reinforced portion of said mop body.

The mop head has a centrally disposed bridge portion 11, preferably pressed upwardly therefrom, and ears 12 struck out and pressed downwardly on opposite sides of the bridge 11, the bottom of these ears preferably terminating above the lower flat part 13 of the head. The mop head may be further reinforced by pressing the inner body portion 14 upwardly.

The mop handle 15 has a socket member 16 secured thereto in known manner by a screw 17 and a bolt 18 passing through ears 19 formed in the separated parts of the tubular portion 20 of said socket member, which is also provided with spaced ears 21, each having a stop projection 22 engageable with the head to limit the upward inclination of the mop handle relative to the head.

A pivot bolt 23 of any suitable construction, such as a screw-bolt provided with a nut 24, passes through the ears 21 of the socket member and the ears 12 of the head.

It will be observed that the ears 21 of the socket member straddle the bridge portion 11 of the head and the downwardly projecting ears 12 and the pivot bolt 23 is disposed below the bridge, with the result that the clamping pressure which may be exerted by the bolt to keep the handle in its adjusted position is resisted by the bridge and the body of the head and that this bridge, being of arched construction, is well adapted to resist these pressures. Furthermore, the ears are formed integral with the bridge and body in an arc or segmental-shaped form coextensive with the width and depth of the bridge, with the result that the ears are relieved of undue bearing strains and the pivot bolt may be

repeatedly tightened up without danger of the ears flexing inwardly and preventing an efficient holding of the handle in the desired adjusted position. It is also to be noted that 5 these ears are not formed by merely bending them up in the form of flaps from the head but are formed by drawing portions of the head inwardly as the bridge portion itself is formed.

10 The operation of the mop is similar to others of this general type, the pivoting of the handle enabling the mop to be used in places where the rigid handle mop cannot be readily manipulated and permitting of 15 the setting and maintaining of the handle in the desired angular position relative to the head for its efficient use.

I desire it to be understood that this invention is not to be limited to any particular form 20 or arrangement of parts except in so far as such limitations are included in the claims.

What I claim as my invention is:

1. In a mop, the combination of a mop head 25 of sheet-metal having an arched bridge portion and arched side portions coextensive with the bridge and forming pivot ears, a handle having an attaching member provided with pivot ears straddling the ears of said head, and a pivot member passing through 30 said ears.

2. In a mop, the combination of a mop head 35 of sheet-metal having an upwardly arched bridge portion and arched side portions coextensive with the bridge and forming pivot ears, the lower edge of said ears terminating adjacent the bottom portion of said head, a handle having an attaching member provided with pivot ears straddling the ears of said head, and a pivot member 40 passing through said ears.

3. In a mop, the combination of a mop head 45 of sheet-metal having a bridge portion with pivot ears depending therefrom, a handle having an attaching member provided with pivot ears straddling the bridge and ears of said head, and a pivot member passing through said ears below said bridge.

In testimony whereof, I affix my signature.

50

MAX P. JANISCH.
